UNITED STATES PATENT OFFICE

CLARENCE P. FOLSON, OF DAYTON, OHIO, ASSIGNOR TO DAYTON BEATER AND HOIST COMPANY, OF DAYTON, OHIO, A FIRM COMPOSED OF LEE E. HALTERMAN AND CLARENCE P. FOLSON

DRIER TANK

Application filed April 7, 1921. Serial No. 459,493.

This invention relates to rendering tanks and driers for the reception of fishery and packing house refuse and offals for salvaging oil and greases and heat treating the residue for tankage or fertilizer.

The object of the invention is to simplify the structure as well as the means and mode of operation of such rendering and drying tanks, whereby they will not only be cheapened in construction, but will be more efficient in use, uniform in operation, comparatively automatic in action, and unlikely to get out of repair.

A further object of the invention is to provide a device of the character described, which will be economical in its operation, and which will effect the rendering and drying of the mass of material in the shortest possible period of time.

A further object of the invention is to afford improved means for uniform heating and cooking of the mass, and whereby the cooking period will be minimized.

A further object of the invention is to provide for the agitation and separation of the cooked and partly dried mass, whereby the mass of material will be not only more or less finely separated, during the operation, but the dried portion will be progressively separated from the moist mass as the operation progresses.

With the above primary and other incidental objects in view as will more fully appear in the specification, the invention consists of the features of construction, the parts and combination thereof and the mode of operation or their equivalents as hereinafter described and set forth in the claims.

Referring to the drawings, Fig. 1 is a vertical sectional view of the assembled rendering tank and drier forming the subject matter hereof. Fig. 2 is a detail sectional view illustrating a modification of the construction shown in Fig. 1.

Like parts are indicated by similar char-

acters of reference thruout the several views.

It is quite the common practice to reduce slaughter house and fishery refuse and offals for the purpose of recovering the grease and oils and preparing the residue for use as fertilizer by subjecting such refuse and offals to a cooking operation within a closed tank to which live steam is admitted under pressure. In the usual process, the oils and greases released by the cooking operation float on top of the fluid or semifluid mass, which is saturated by the inherent water or liquid and the water of condensation. The grease and oils floating on top of the mass are drained off thru suitable outlet drains located at the approximate fluid level of the charge of material. Any additional oils or greases remaining are drained off by adding water to the mass to raise the fluid level to that of the outlet. In any event this operation leaves the cooked mass of material in a saturated condition necessitating a long drying period and the expulsion of a maximum quantity of vapor. Ordinarily this moisture is extracted subsequent to the extraction of the oils and greases by subjecting the mass to steam heat by circulating the steam thru a jacket surrounding the cooker tank, and at the same time exhausting the vapors from the interior of the tank and increasing the drying operation by inducing a partial vacuum therein.

The present apparatus and process involved in its use contemplates the immediate separation of the liquid from the mass of material during the cooking operation, which liquids are drained off to a settling tank, wherein the water and grease or oils are subsequently separated, leaving the mass of material in a partially dehydrated condition. In other words, the liquid and moisture is separated from the mass of material and the mass drained during the cooking operation, leaving the mass of material in a solid state.

with all excess moisture removed before the drying operation is begun.

The present invention further contemplates the separation of the mass of material as rapidly as portions of it become partially dry by depositing such partially dry portion from the bottom of the mass, allowing the moist upper portion to descend into the more heated zone, thereby materially increasing 10 the rapidity with which the cooked material is dried.

Referring to the accompanying drawings, in which is shown the preferred but not necessarily the only form of embodiment of the 15 invention, 1 is an upright cylindrical tank, having a somewhat enlarged base portion 2, surrounded by a steam jacket 3, having a sub bottom 4, spaced from the bottom of the tank to afford an intermediate steam space 5, about 20 the lower walls and beneath the tank or container. The tank is divided at a mid height point by a perforated diaphragm 6 into an upper or cooking compartment 7, and a lower or drier and drainage compartment 8. The 25 diaphragm or perforated wall 6 dividing the compartment 7 and 8 is of a somewhat dome shape or concavo-convex with its convex side uppermost. The periphery of this diaphragm or division wall is downturned or 30 flanged as at 9 and attached in spaced relation with the side walls of the tank 1. This provides an intermediate annular space 10, between the margin of the diaphragm 6 and the wall of the tank to permit the passage 35 of fluid from the cooking mass and obviate any retention of the liquid in the upper compartment. It is to be noted that the convex shape of the diaphragm or division wall 6 tends to drain the liquid and moisture in the 40 cooking mass contained within the upper compartment 7 outwardly toward this annular exit 10, thus insuring the escape of the liquid and moisture, which might otherwise be prevented from draining thru the perfor- 45 ations of the diaphragm 6.

Extending axially thru the lower compartment 8 is a rotary shaft 11 carrying at its upper end within the cooker compartment 7 an agitator 12, comprising radially disposed 50 arms having upward projecting fingers 13. This shaft also carries a like agitator within the lower compartment 8, comprising a radial arm 14, and the upwardly projecting fingers 15. These agitators are rotated 55 within the respective compartments by the rotation of the drive shaft and serve to stir, break up and redistribute the material contained in the respective compartments. These agitators may be driven thru any 60 suitable power connection as for instance by means of a bevel gear 16, on the lower end of the drive shaft, intermeshing with a corresponding gear pinion 17 carried upon a power shaft 18.

65 The mass of materials to be reduced is in-

roduced into the cooker compartment 7 thru the charging door 19 in the top of the tank, and rests upon the perforated diaphragm or wall 6. Live steam is then admitted thru the steam supply pipe 20 to the cooker compartment above the level of the mass therein, and also at the same time steam is admitted thru the inlet pipe 21 to the compartment 8 beneath the mass of material to be cooked. The diaphragm or wall 6 being perforated permits the steam from the compartment 8 to penetrate the mass from the bottom while the steam admitted to the top of the cooker compartment 7 being likewise under pressure is caused to penetrate the mass from the top. By this means the mass of material is subjected to uniform and rapid cooking. It will be understood that during this cooking operation, usually the agitator is at rest. As the cooking operation progresses the liquid, 80 juices and water of condensation from the cooking steam together with the liberated oil and fat will drain thru the perforations of the diaphragm 6 and the exit space 10 into the lower compartment 8, which will serve as a reservoir for the fluid extraction. At the completion of the cooking operation, the mass of material in the cooker compartment 7 will be but moist or partially dry, containing little or no free liquid, the moisture and liquids thereof having to a very considerable extent been drained into the lower compartment 8, whence they are conducted thru the outlet or drain pipe 22, to a suitable 90 settling tank. No attempt is made to separate the grease and oil from the water within the cooker, but the intermixture of oil and grease with the water is conducted to the settling tank or other separator (not shown).

The cooking operation being completed, 100 and the liquid drained from the bottom of the tank, the supply of steam is disconnected from the chambers 7 and 8 and in lieu thereof, steam is supplied to the jacket space 5, surrounding the lower compartment 8. This 105 supply of steam is admitted to the jacket thru a supply conduit 23. At the same time the agitators are set in operation to stir the cooked mass and a vacuum pump 24 operating thru a conduit 25 communicating at 110 with the top of the cooker chamber 7, exhausts from the cooker chamber 7 the vapors resulting from desiccation of the mass of material producing a partial vacuum within the tank and materially increasing the rapid- 115 ity of evaporation of any remaining moisture. This exhaustion of vapors from the top of the cooker chamber also tends to draw the heated air and vapors from the compartment 8 thru the mass of cooked material. 120 As the lower part of the mass becomes partially dry, the agitation due to the movement of the arm 12 and fingers 13 breaks up the partially dried material, causing it to be deposited thru the perforations of the dia- 125 130

phragm or wall 6 into the lower compartment 8.

The lower portion of the mass being subjected to greater heat is more thoroughly dried than that higher up in the mass and as the drying progresses the dried particles are crumbled or broken away at the bottom from the less dry portions above by the actions of the agitator and such separated portions are deposited through the perforated bottom into the lower compartment. This separation and deposit of the dried portion is progressive for as the separated dried portions are deposited the mass settles within the upper compartment thus bringing each succeeding level of the material progressively into the more highly heated zone, the separation of the material and its deposit into the lower compartment being thus progressively continued until the entire mass is so acted upon.

The size of the perforations of the diaphragm 6 may vary according to the character of the material operated upon. It has been found in practice that openings of approximately one inch in diameter will meet the usual conditions of use. However, larger or smaller openings may be provided, to adapt the device to the reduction of coarse or fine material. The deposit of materials thru the perforations of the diaphragm will permit the mass to descend within the cooker chamber 7, while the partially dried material deposited is collected in the lower compartment 8, where it is agitated by the rotation of the arm 14 and fingers 15 and the drying completed. To increase the drying action, there is provided a jacket 27 surrounding the lower portion of the compartment 7, which jacket communicates at its lower end thru suitable openings 28 with the compartment 8. This jacket 27 is connected thru a branch line 29, having therein a control valve 30 with the main section or vacuum conduit 25. By opening the valve 30 the vapors are not only exhausted from the top of the cooker compartment 7 but also thru the connection 29 and the jacket 27, such vapors are exhausted from the lower compartment 8. These heated vapors being drawn from the compartment 8 thru the jacket 27 surrounding the mass of material within the compartment, tends to further increase and distribute the heat thru such mass, utilizing the exhaust vapors and affording a maximum drying action. This drying operation is continued until the dried material subdivided by the agitation of the arms 12 and 14 is deposited thru the perforations of the diaphragm 6 into the lower compartment 8, where it is subjected to further agitation and heat due to the circulation of steam thru the jacket space 5, until thoroughly dried and reduced to a coarse granular form. The dried material is then removed thru a drawing door, 31.

In Fig. 2 there has been shown a modification of the construction, wherein the auxiliary heating jacket 27 has been omitted, and the vacuum connection is made thru a conduit 29' directly to the compartment 8.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms, or modifications within the legitimate and valid scope of the appended claims.

Having thus described my invention, I claim:

1. In an apparatus of the character described, a tank having imperforate side walls and a perforate diaphragm dividing the tank into upper and lower compartments, the lower compartment being of greater diameter than the upper compartment an annular jacket surrounding the lower portion of the upper compartment in spaced relation with the walls thereof forming a concentric chamber surrounding the lower portion of the upper compartment said chamber having intercommunication with the lower compartment, means for supplying heating medium to the upper compartment to effect the cooking of a mass of refuse in said upper compartment and also for supplying heating medium within the surrounding jacket of the upper compartment and means for progressively depositing the cooked material through the perforated diaphragm between said compartments into the lower compartment.

2. In an apparatus of the character described, a tank separated into two intercommunicating compartments one above the other a perforated diaphragm separating said compartments, steam supply conduits leading to the respective compartments, and an exhaust conduit also communicating with both compartments—and a power driven agitator in the upper compartment for effecting the progressive separation of the desiccated solid material from the remaining moist material operated upon and the discharge thereof from the upper to the lower compartment.

3. A drier tank, a perforated diaphragm therein dividing the tank into an upper receiving compartment for the material oper-

ated upon, and a lower accumulating compartment for the treated material means for admitting live steam to the tank during treatment of the material and external means for heating the contents of the compartments 5 for evaporating the moisture therefrom, and an agitator in the upper compartment for breaking up the mass of drying material and separating the more thoroughly dried portions 10 from the remaining moist portions thereof, and for effecting the deposit of the separated dried material through the perforated diaphragm into the accumulating or lower compartment.

4. In an apparatus of the character described, a cooker tank for refuse a perforated diaphragm dividing the tank into a cooker compartment above the diaphragm and an accumulator compartment for the treated material located below the diaphragm, means for heating the contents of the cooker compartment and subsequently dehydrating the same, an exhaust conduit for leading off from the tank vapors of 25 evaporation while effecting the dehydration of the cooked material, means for effecting the gradual deposit of the dehydrated material from the cooking compartment into such an accumulating compartment and heating 30 means for the accumulating compartment additional to that of the cooking compartment for subjecting the deposited material to further heat treatment.

5. In an apparatus of the character described, a tank, a convex diaphragm therein, the convex face of which is turned upwardly separating the tank into upper and lower compartments, there being intercommunicating openings between the compartments at 40 the periphery of the convex diaphragm in proximate relation to the connection of the convex diaphragm and the walls of the tank, steam supply and exhaust connections to each compartment of said tank, and agitator means 45 in both said compartments for the contents thereof.

6. In an apparatus of the character described, a tank, a perforated diaphragm dividing the tank into upper and lower inter- 50 communicating compartments, means for heating the contents of the upper compartment to cook the same, the liquid contents being drained from the mass of material during the cooking operation, means for subsequently heating the lower compartment independent of the heating of the upper compartment the heat of the lower compartment being transmitted to the lower portion of the mass of drained material contained in the 55 upper compartment, to effect the drying of such material, an agitator acting upon the partially dried material comprising the bottom of the mass in the upper compartment to separate such partially dried material 60 from the remaining moist portion thereof and

for forcing such separated material through the perforated diaphragm into the lower compartment.

7. In a heat treating apparatus for tankage and the like, a tank, a perforated dia- 70 phragm dividing the tank into an upper cooking and a lower drying compartment, such drying compartment being located beneath the cooking compartment and communicating therewith through said perforated dia- 75 phragm, an annular extension of the drying compartment exteriorly surrounding the cooking compartment to a mid-height point, an external heating jacket surrounding the drying compartment and a conduit for admitting live steam to the interior of the cooking compartment, agitating means within the cooking compartment and an exhaust conduit for exhausting vapors arising from the mass of material during the cooking and subsequent drying operation. 80

8. In a heat treating apparatus for tankage and the like, a tank, a perforated dia- phragm dividing the tank into superposed cooking and drying compartments agitating 90 means overlying said diaphragm, an annular heating jacket surrounding the lower portion of the cooking compartment in spaced relation to a mid-height point forming an annular chamber exteriorly of the cooking compartment and which has communication with the drying compartment, an external heating jacket surrounding the drying compartment, a conduit for admitting live steam to the interior of the cooking compartment, and 100 means for exhausting the vapors from said tank.

9. In an apparatus of the character described, a tank, a perforated diaphragm dividing the tank into two superposed concentric intercommunicating compartments, an agitator in each compartment, steam supply and exhaust conduits communicating with both compartments of the tank, and means for subjecting the material to external dry- 110 ing heat during its agitation. 105

10. In an apparatus of the character described, a tank including a compartment having a convex perforated bottom, an agitator located adjacent to the convex face thereof conforming in its movement to the convexity of the bottom of the compartment, means for heating the contents of the compartment and means for exhausting the vapors therefrom and means for actuating the agitator to stir 115 the material operated upon in the zone immediately above said perforated convex bottom and to force such material through the perforations thereof. 120

11. In rendering apparatus, a pressure- 125 tight cylindrical tank, comprising an upper section and a lower section, the upper section being of smaller diameter than the lower section, said tank having a bottom shaped convex upwardly, a heating jacket surround- 130

ing the lower portion of said lower section, a convex perforated plate located at the lower end of said upper section and in spaced relation to the side wall of said tank, separate
5 means for introducing heating fluid into each of said sections, separate means for exhausting gases from each of said sections, means in each section for agitating materials therein, means for introducing material to be treated in the upper section, and separate means in said lower section for respectively removing residual solids and liquids therefrom.

In testimony whereof, I have hereunto set my hand this 28th day of March A. D. 1921.
